COMPRESSION RHEOSTAT.

Application filed June 4, 1919, Serial No. 301,710. Renewed November 12, 1925.

This invention is an electric controller which effects an entire and uniform control of electric currents. It can form an instrument by itself or it can form part of another instrument or device. It can entirely interrupt or it can regulate electric currents and can do it very rapidly or slowly.

The change in electric conductivity is brought about by differences in contact of electric conducting bodies, according to the well known effect. In my instrument this principle of difference of contact is accentuated and controlled by suitable means, to be here described as the principal means of bringing about this great variation of contact of electric conducting bodies. The special electric resistance material consists of an intimate and uniform mixture of electric conducting matter in a finely divided state and electric non-conducting matter in a fine state, part of which must be of a resilient nature so as to impart a compressible and resilient nature to the entire composition. When this material is under no or slight compression, its constituent particles are in very light contact and its electric conducting particles touch very lightly or not at all. The conducting and non-conducting particles being all interspersed there can be but very minute if any conducting paths and the material in that condition is practically an insulator.

As increasing pressure is applied the volume of the material grows smaller, the particles come more and more into contact, paths of conductivity form and grow larger, as more conducting particles come into contact and into more intimate contact, and the electric conductivity, therefore, increases. When the material is firmly compressed the conducting particles are in close contact, enough of these particles are in close contact to form a path of good conductivity, and the material in this condition is a fairly good conductor, the resistance may be only a small fraction of an ohm.

The material need not be made of any particular substances but must have a general nature and identification of compressibility, resiliency and uniformity of constitution. It must have the same proportion and the same density of material throughout its mass. It should have the same proportion of material, the conducting and non-conducting matter interspersing, so that

there should be no undue amount of conducting matter by itself to form a path of good or fair conductivity. Such paths would permit a flow of electricity at all times even under light or no pressure, and with currents of considerable amounts there would be rapid heating of these paths and a rapid increase of conductivity. It would soon result probably in the destruction of the material by a very high temperature and there 60 certainly could be no control of current by means of such a material. There must also be a general regularity, at least, of density of material. There must be no packing of material as this would result in an area of good 65 conductivity with the same deleterious effects in a lesser degree. Slight irregularity of density is not harmful.

To obtain a material of the above nature the material should be made of suitable substances and by suitable means. With substances of a non-adhesive nature such a material can be readily made. Mere thorough mechanical mixtures will be sufficient. Mica in the form of flakes or slivers and carbon or 70 graphite in a fine form makes a very efficient mixture. In particular I prefer a mixture of the finer mica flakes and graphite flakes. When however the non-conducting matter is of an adhesive nature as the longer fibres of 75 asbestos particularly are, a special process must be employed which is also specially applicable to the shorter fibres, as follows:

The fibrous material preferably in a loose condition, is immersed for a suitable time, 80 in a liquid, preferably water, in which electric conducting particles, carbon or graphite preferred, are kept in motion by suitable means as by boiling the liquid or other agitation of the liquid. Because of the adhesive 85 ness of the fibrous matter and the non-adhesive nature of the conducting particles, and the loose condition in which the fibrous matter is from, which condition is accentuated by the treatment, the tendency is for the conducting particles to enter into contact with 90 and form a coating over each and every fibre, the coating being a uniform film, and the particles touching lightly, when they touch at all. The material is then separated from 95 the liquid and dried, when it will form a material consisting of an intimate and uniform combination of fibre and conducting particles.

On separating the material from the 100

liquid, when it is in a very pliable condition, it should be cast into the form of a thin layer and then dried. It then forms a soft felt or mat like material of practically uniform density adhering together in the form in which it was cast, and is a specially efficient and suitable resistance material. This liquid treated combined resistance material could also be used in the form of cloth. The short fibrous material, that is the mixture or combination of short fibers and conducting particles, can be given a felt or mat like form by coating it on metal supports, which can be effected by means of cement, or by merely drying the material on the metal supports.

A suitable portion of this material in any of its different forms or in a combination of its different or some of its different forms, together with suitable accessories, makes an efficient regulator for small currents and for currents of low voltage. With currents of higher voltage and considerable amperage, as currents of the arcing value, very complicating and important phenomena and effects would appear. On closing the electric circuit the current would rise rapidly and would destroy the material by a high temperature unless the current was interrupted, as by blowing a fuse, etc. This rise in conductivity seems to be due to particles of conducting matter cohering, that is, joining firmly, making good contacts, and therefore areas of good conductivity. These areas of cohering effects and high temperature rapidly spread, with the result as stated above. These effects however take place only with the higher voltages above 20 or 25 when the amperage is large in proportion at the same time. Therefore, by dividing the resistance element into sections, so that the drop in voltage should not exceed the proper amount in relation to the amperage these effects will be obviated.

The lower the current flow in amperes the higher the voltage can be. When the current is only about a half ampere, the voltage can be over one hundred. With low voltages the amperage may be very large, it is possible also to arrange the sections in parallel so as to give a low amperage and high voltage, that is to split the amperage and not the voltage.

These sections consist of a portion of resistance material between containing walls, as a resistance material separated by intersecting walls, or portions of material may be placed in separate containers, electrically connected. Provision should be made for permitting the escape of heat, and also for permitting slight expansion in the containing wall away from the material to maintain a uniformity of pressure, as the material also expands slightly with heat. This however is not marked and is not important with the non-fibrous resistance materials.

The drawings show a very convenient form of intersecting or containing wall. A piece of metal is bent over into a form of double plate with an air space between as shown. It thus has ample ventilation and radiating surfaces, and can expand away from the contained resistance material. The resistance element consists of metal plates and thin mats of resistance material placed alternately. The plates and mats of resistance material are movable, so that pressure applied to one section is transmitted to all. The variation of conductivity takes place not only by means of the differences of contact of the conducting particles of the resistance material, but also by the variation of contact between the conducting particles of the resistance material and the metal plates. The variation in pressure is here obtained by means of a regulating screw, but may be obtained by other means.

This rheostat is very efficient, even ordinary mixtures of fibre and fine conducting matter, not liquid treated, but used in the loose felt condition between these plates will make a fairly good rheostat for some purposes. The liquid treated material is however the only really efficient fibrous material and should be used, as in conjunction with the intersecting plates, it gives a uniform and entire range of resistance, and for the larger apparatus is the material to be preferred over all others.

For small amounts of current as when used in a socket form for dimming incandescent lights the mixture containing the non-fibrous matter is preferable as it is easiest handled. In particular I use the mixtures containing mica. The drawings show a combination of rheostat and lamp socket. The variation in contact here takes place between the conducting particles of the mixture and the regulating screw which is also one of the electric contact parts. This screw also acts as part of the container confining the material, and preventing any loss of it from the receptacle. This device contains means for breaking the electric contact at a point of light pressure, and for short circuiting the resistance element at a period of firm pressure.

This appliance has what is known as an Edison socket for receiving the electric lamp or other such device, and a screw plug for fitting into an Edison socket. No special means for heat radiation or ventilation is provided in this instrument, although such means could be easily installed and would be found helpful for larger currents than are ordinarily used in incandescent lamps. For lamps such as are ordinarily used in residences and such devices, the socket rheostat as substantially shown is sufficient.

It will be seen by these descriptions, that the variation in conductivity is brought

about not only by the conducting particles of the resistance material, but also by the electric contact parts acting in conjunction with the conducting particles, and by the intersecting parts or container parts and the conducting particles, there may be also relatively large conducting bodies intersecting the resistance material, and assisting the variation in conductivity. These relatively large conducting bodies increase the power of higher resistivity in the circuit by reason of their relatively smooth surface, and the lack of tendency of the conducting particles to cohere or come in close contact therewith.

Under light pressure the conducting particles are in lighter contact with these larger conducting bodies, which are usually or always metal, than they are with each other, hence the higher resistivity. This applies particularly to the fibrous materials in which the conducting particles are in closer contact than the conducting particles in the non-fibrous mixtures.

By reason of the efficacious action and assistance given by the contact, and intersecting parts and the use of separate containers, considerable efficiency can be obtained by the use of these means in conjunction with other resistance material than that invented by me.

Metal plates of the general type as that shown in the drawing would be very efficient in maintaining the same conditions of temperature and pressure and breaking up cohering effects. Electric contact parts, having a spring effect or of special shape would also be effective in connection with relatively large bodies with electrically sensitive contact surfaces, that is bodies which vary their electric resistance through variation of contact, as bodies of carbon or graphite or containing carbon or graphite and a non-conducting matter. Such contact parts as described would be inserted between such poorly conducting parts or bodies as those of the so called graphite of commerce.

This case is related to my companion case, Serial No. 411,778, filed June 4, 1919, issued concurrently herewith and the claims generic to the two applications are presented in the companion case.

The following is what I consider a good means of carrying out this invention and the following drawings should be referred to for a complete understanding of the specification which follows:—

In the drawings:—

Fig. 1 is a side view in elevation of the preferred form of this invention illustrating the device constructed for use in ordinary electric lamp sockets.

Fig. 2 is a vertical sectional view through Fig. 1.

Fig. 3 is a vertical sectional view through the device taken at right angles to Fig. 2.

Fig. 4 is a horizontal sectional view

through the center of the device illustrating the compressor, screw, and other parts relating thereto, removed.

Fig. 5 is a view partly in section, of a modified form of controlling knob of the device.

Fig. 6 is a fragmentary view similar to Fig. 2, illustrating the use of a fibrous resistance element and

Fig. 7 is a horizontal sectional view through a modified form of rheostat illustrating the same adapted for use for heavier currents.

Similar reference numerals indicate like parts in all of the figures where they appear.

Referring to the drawings in detail the numeral 1, designates the main body of the device which is preferably formed of porcelain or a similar insulating material. This body may be cylindrical as illustrated in Figure 4 and provided at one end with a reduced extension or plug 2. Extending longitudinally through the plug 2 is a bore 3 the inner end of which communicates with a transverse passage 4 formed in the plug and body which passage opens out through the side thereof. The transversely extending centrally exposed passage 5 is formed in the body 1 and extends at right angles to the passage 4 previously described. From a point about midway of the length of the passage 5 there is provided an enlarged bore 5^a and a groove 6 as clearly illustrated in Figure 2. Extending longitudinally through the body 1 from the under side thereon and off set from the longitudinal axis is an aperture 7, the inner end of which communicates with the groove 6. Parallel with the opening 5 is a transverse bore 8 arranged slightly beneath said opening and this bore 8 extends from the inner wall of the groove 6 through the inner wall of a recess 9, formed in the body immediately beneath the rear terminal of the passage 5. A recess 10 is formed in the under side of the body and is slightly off set from the center thereof.

Surrounding the plug 2 is a threaded shell 11 having formed on the inner end thereof, a tongue 12 to which is connected a contact strip 13. This strip extends across the rear end of the passage 5 and is provided with an inwardly off set portion 14 which seats in the recess 9 herein before described. Extending through the off set portion 14 is a screw 15, the inner end of which is threaded into a contact plate 16 arranged against the inner wall of the groove 6. It will be understood that this contact plate is surrounded by a suitable insulating material 17 as will be clearly seen upon reference to Figures 2 and 4. Seated in the enlarged bore 5^a is an internally screw threaded bushing 18 which is notched at its extreme inner end to receive the insulation 17 and this bushing is

held in place by a screw 19 which passes through the aperture 7 and contacts at its outer end with a threaded shell 20 which is secured to the lower end of the body 1.

- 5 A screw 21 is threaded into the bushing 18 and carries at its inner end an extension 22 which bears against a compression plate 23. This compression plate is slidabie in the passage 5 and is adapted to engage against the 10 resistance material 24 which is disposed between said compression plate and the contact strip 13. The screw 21 is provided on the end opposite the extension 22, with a stem which projects outwardly beyond the side of 15 the body and has attached thereto, a thumb piece 25 by which the device is manipulated.

In order to establish connection between the central contact 26 of the plug 2 and the central contact 27 of the socket 20, a contact 26 is provided with a threaded stem 28 which extends through the bore 3 and into the passage 4. The inner end of this stem is threaded into a connection strip or bar 29 the lower end of which terminates in the 25 contact 27 which is provided with a hook 30 for engagement in the recess 10. In order to avoid short circuiting the shell 20 with the strip 29, the said shell is recessed as at 31 at the point where the contact strip enters 30 the same.

An enclosing casing for the device consisting of a pair of telescopic cylindrical shell members 32 and 33 is provided and the member 32 is formed at its upper end with 35 an inturned flange 34. The lower edge of this shell member is recessed to accommodate the shank of the screw 21 as at 35. The shell member 33 is formed at its lower end with a reduced cylindrical extension 36 which is 40 adapted to enclose the socket 20 and like the shell member 32, the upper end of the member 33 is formed with a recess which alines with the recesses 35 to accommodate the shank of the screw when the device is 45 assembled. Each of these members is provided with a lining 37 which is pressed therewith and formed of a suitable non-conducting or insulating material.

In Figure 6 there is illustrated a device of 50 the same construction as that shown in Figure 2, but instead of the finely divided filling or resistance material 24 a fibrous resistance material 38 is used. In the use of such material it has been found desirable to allow 55 for expansion thereof and for that reason I provide spaced U shaped plates 39 forming a follower. These plates are disposed between layers of the resistance material and not only allow for expansion when the material becomes heated, but also provides a 60 radiating surface to disburse the heat created by the passage of current through said fibrous material, and further these plates operate as de-coherers, separating the 65 material and particularly sections of mate-

rial after each operation or when the pressure is released. In the modified form of the invention illustrated in Figure 7, the device is illustrated as constructed for use with currents in excess of that for which the rheostat previously described is built. In this type of rheostat or controller, a casing 40 of ebonite or any other suitable non-conducting and insulating material is provided and one end wall of said casing carries a contact 70 plate 41 while the opposite end wall is formed with an opening to receive an internally screw threaded bushing 42. A follower plate 43 formed of any suitable material is provided and carries on its inner face a contact plate 44 while the outer face of said follower is provided with a swiveled head 45 to which the screw 46 is attached. This screw 46 operates through the bushing 42 and is provided at its outer end with a 75 suitable thumb piece or crank 47 by means of which the screw may be turned for adjustment of the plate. The resistance material as designated by the numeral 48 is arranged in layers or sections between the 80 arched members 49 which may be resilient to a greater or less degree to allow for expansion and contraction of the fibrous material 48 and to rapidly radiate and disperse any heat created by the rise of temperature 85 of the fibrous material due to the passage of current therethrough. A suitable movable contact is connected to the plate 44 and when the material reaches a predetermined point of compression where the flow of current 90 therethrough is practically at its maximum the said movable contact engages a stationary contact attached to the plate 41 thereby 95 short circuiting the resistance material.

In Figure 5 there is shown a winding 100 drum which may be substituted in lieu of the thumb piece 25 on which drum is wound cord 50 having its opposite ends extended and provided with the knobs 51. It will thus be seen that upon pulling one or the 105 other of said knobs, the drum may be rotated and the screw 21 adjusted.

In operation it will be seen that the plug 20 threaded into an ordinary electric socket and an ordinary lamp may be secured in the 110 socket 20. The central contact of the lamp will engage the contact 27 while the contact 26 will engage the central contact of the socket and in this way the strip 29 will act to create a direct path for the flow of current through one central contact to the other. Current entering the socket through the shell thereof, will pass through the shell 11 of the plug 2 and thence downwardly through the plate 13. Upon advancing the 120 screw 21 by rotating the knob 25, the plate 23 will compress the finely divided resistance material 24 and gradually create paths of 125 conductivity through which the current may enter the follower 23 and extension 22 of 130

the screw 21 and thence pass through a bushing 18 and screw 19 to the socket 20. It will thus be seen that by regulating the pressure of the plate or follower 23 and the compression of the resistance material 24, the amount of current passing through the socket may be varied. It will be understood that when the screw 21 is advanced to a point where substantially maximum current passes through the resistance material 24, the said screw will contact with the plate 16 thereby short circuiting the resistance material as the current will enter the screw and bushing 18 through the screw 9.

Upon turning the screw 21 to retract the same it will be evident that the same will be moved away from the plate 16 and the current will again pass through the resistance material 24 and as compression becomes lessened it will be evident that paths of conductivity therethrough will be reduced until such time as little or no current will flow through the device. The operation of the device illustrated in Figures 6 and 7 is essentially the same as that previously described.

In practice it has been found that the resistance elements used in connection with the rheostat described in the foregoing are most efficient when prepared from about equal quantities of mica flakes or mineral or zinc wool and flaked carbon or graphite intimately and uniformly mixed. It has been found that two such substances, one of a conducting and the other of a non-conducting and resilient nature, having approximately the same specific gravity when thoroughly mingled will form a very efficient resistance element. Mica flakes and carbon or graphite in a finely divided state when intimately mixed also forms an excellent resistance element and has the necessary resiliency.

Other modifications may be made within the scope of the appended claims without departing from the principle or sacrificing the advantages of the invention.

What I claim is:

1. In a compression rheostat, a stationary contact plate, a movable contact plate, finely divided resistance material, a rigid retaining wall confining said material between said plates, means to advance the movable plate to compress the material and create paths of conductivity therethrough and means to allow for the expansion of said material when the same becomes heated and to radiate the heat created therein.

2. A device as set forth in claim 1 in which expansion and radiation are provided for by forming one of said contact plates of relatively thin metal.

3. A compression rheostat comprising a casing, a contact plate at one extremity of the casing a movable contact element ar-

ranged in opposed relation to the contact plate, means to move the movable contact element toward or away from the plate, layers of resilient fibrous resistance material between the contact plate and the contact element and a plurality of spaced parallel plates of a resilient conducting material arranged between the layers of resistance material to allow for expansion of the resistance material and to conduct away heat.

4. A compression rheostat comprising a casing, a stationary contact at one extremity of the casing, a movable contact in opposed relation to the stationary contact, layers of resilient compressible resistance material arranged between the contacts and pairs of spaced parallel plates of resilient conducting material arranged between the layers of resistance material whereby heat generated in the resistance material may be radiated and any expansion of the resistance material due to its heating tendencies may be compensated for.

5. In a compression rheostat, a compartment having a displaceable closure, finely divided resistance material divided in said compartment, means adapted to displace said closure for compressing said material to create paths of conductivity therethrough and means contained within said compartment to allow for the expansion of said material when the same becomes heated and to radiate the heat created therein.

6. In a compression rheostat, a container having compressible resistance material housed therein, a bodily movable follower plate, for subjecting the resistance material to compression, and means for counteracting the cohering effect produced by thermal and electrical forces in the rheostat in order to maintain adjustment of the resistance.

7. In a compression rheostat, a container having compressible resistance material housed therein, means for subjecting the resistance material to compression in order to adjust the resistance thereof, comprising metallic plates spaced apart but connected together, at least one of said plates contacting with said material and yieldable to compensate for the influence of thermal and electrical forces in the rheostat.

8. In a compression rheostat, a container having compressible resistance material housed therein, means for subjecting the resistance material to compression, and means for counteracting the cohering effect produced by thermal and electrical forces in the rheostat in order to maintain the adjustment of the resistance.

Signed in the city of New York, county and State of New York, this 25 day of April, 1919.

AARON MICAH LEVY.
